MULTIPLE SOCKET ELECTRICAL CONNECTION DEVICE

Filed April 14, 1950

UNITED STATES PATENT OFFICE

2,627,535

MULTIPLE SOCKET ELECTRICAL CONNECTION DEVICE

Rathbun B. Squires, Forest Hills, Pa., assignor to
Westinghouse Electric Corporation, East Pittsburgh, Pa., a corporation of Pennsylvania

Application April 14, 1950, Serial No. 155,974

5 Claims. (Cl. 173—334)

1

This invention relates to electrical connection devices and it has particular invention to connection devices suitable for connecting and reconnecting large numbers of electrical circuit elements.

In accordance with the invention, a number of receptacles are mounted on a panel. Each of the receptacles is designed for reception of an electroconductive plug. A U-shaped electroconductive spring extends between each pair of receptacles for the purpose of electrically connecting pairs of plugs which are located in such receptacles. The end receptacle in a row may be additionally provided with electroconductive springs for the purpose of establishing further connections for plugs located in the end receptacles. If desired, a single receptacle also may be provided for reception of the plugs.

It is, therefore, an object of the invention to provide a compact, improved connection device for establishing connections for large numbers of circuit elements.

It is a further object of the invention to provide a connection device which includes a plurality of receptacles for electroconductive plugs wherein each pair of receptacles has a U-shaped electroconductive spring extending therebetween for the purpose of connecting plugs located in the receptacles.

Other objects of the invention will be apparent from the following description taken in conjunction with the accompanying drawing in which:

Figure 1 is a view in plan with parts broken away and parts shown in section of a connection device embodying the invention;

Fig. 2 is a view in section taken along the line II—II of Figure 1;

Fig. 3 is a view in plan of a modified connection unit embodying the invention;

Fig. 4 is a schematic view showing connections established by a connection device embodying the invention; and

Fig. 5 is a schematic view with parts in section showing a further embodiment of the invention.

Referring to the drawing, Fig. 1 shows a panel P having a number of receptacles associated therewith. Although any desired number of receptacles may be employed, the invention may be described adequately by reference to four receptacles 1, 3, 5 and 7 as illustrated in Fig. 1.

Each of the receptacles is designed for receiving an electroconductive plug 8. The plug may include an electroconductive pin 8a which has a rounded nose 8b and a peripheral groove 8c adjacent the nose. The pin 8a extends into an insulating sleeve 8d wherein it is electrically connected to one end of a conductor C. The con-

2

ductor C may have a similar plug at its remaining end, but in the preferred embodiment the remaining end is connected to a circuit component as will be pointed out more fully below.

- 5 The receptacles 1, 3, 5 and 7 include insulating bodies 1a, 3a, 5a and 7a. Since these insulating bodies are similar in construction, it will suffice to describe in detail the insulating body 3a for the receptacle 3.
- 10 The insulating body 3a is of generally tubular construction and may be constructed of any suitable insulating material such as a phenolic resin. The insulating body is secured in any desired manner to the panel P. In the embodiment 15 herein disclosed, the insulating body 3a has a flange 9 which engages the front surface of the panel P (the lower surface in Fig. 1). The remainder of the insulating body 3a projects through an opening in the panel P and includes a threaded portion 11 which is in threaded engagement with a nut 13. By manipulation of a nut 13, the panel P may be secured firmly between the nut and the flange 9.

The insulating body has an opening 15 which 20 extends in a direction transverse to the panel P and which is proportioned for sliding reception of the pin 8a of the plug 8. The insulating body also has passages 17 and 19 which extend in a direction transverse to the axis of the opening 15 through the walls of the insulating body. Longitudinal grooves 21 and 23 are provided in the insulating body. The opening 15 may vary in shape provided it receives satisfactorily the plug 8. It will be assumed that the opening 15 is of cylindrical configurations.

- 25 In order to establish electrical connections between plugs located in the receptacles, a plurality of U-shaped electroconductive springs 25, 27, and 29 are provided. It will be noted that one of the U-shaped electroconductive springs is located between each pair of the receptacles. Since the U-shaped electroconductive springs are all identical in construction, a description of one of the springs 25 will suffice.

The spring 25 may be constructed of any suitable electroconductive material such as resilient copper or phosphor bronze. The legs 25a and 25b of the U-shaped spring are located respectively in the groove 23 of the receptacle 1 and the groove 21 of the receptacle 3. The walls of 30 the grooves constitute flanges which maintain the spring 25 substantially in a plane containing the axes of the openings provided in the receptacles.

Each end of the spring 25 has associated 35 therewith an electroconductive contact member which projects into the opening of the associated receptacle. For example, the contact members

25c and **25d** are secured respectively to the ends of the spring **25**. These contact members may be constructed of any suitable material such as silver buttons or silver-faced pins. The contact members **25c** and **25d** project respectively through the passage **19** of the receptacle **1** and the passage **17** of the receptacle **3** into the openings of the two receptacles.

The design of the spring **25** simplifies the construction of the connecting device and results in a compact and effective assembly. The U-shaped construction provides the equivalent of a long spring in a small space. As is apparent from the drawing, the spring **25** may be slipped into mounted position and removed therefrom by simply withdrawing the contact members **25c** and **25d** from the associated passages and sliding the spring **25** through the grooves **21** and **23** of the associated receptacles. A reverse procedure is followed during assembly of the connecting device.

When a plug **8** is inserted in the receptacle **3**, the springs **25** and **27** are connected to each other through the plug and also are connected to the plug. Consequently, as many plugs as desired may be placed in consecutive receptacles for the purpose of connecting the plugs to each other. If a plug is omitted from one of the receptacles the plugs on each side of the receptacle will be insulated from each other. When the plug **8** is in mounted position the contact members **25c** and **25d** enter the groove **8a** to retain the plug in mounted position and to establish contact therewith.

The end receptacles in a row have only one U-shaped spring associated therewith, whereas the intermediate receptacles have two U-shaped springs associated therewith. For some applications it may be desirable to provide a straight or leaf electroconductive spring **31** for each of the end receptacles. Such a spring may be secured to the end receptacle in any desired manner as by means of bolt **33**. The spring **31** has a contact member **31a** which projects through one of the passages of the receptacle to which the spring is secured. Consequently, upon insertion of the plug **8** in an end receptacle such as the receptacle **1**, the plug is electrically connected to both the spring **31** and the associated U-shaped electroconductive spring **25**. The spring **31** may be connected through a suitable conductor **31b** to any desired circuit component. A spring **31** also is illustrated for the receptacle **7**.

The parts employed in fabricating the connection device of Fig. 1 also may be employed for a single receptacle. For example, in Fig. 3, a receptacle **35** is illustrated which is similar in construction to the receptacle **1** of Fig. 1. However, in Fig. 3, the U-shaped electroconductive spring **25** of Fig. 1 is replaced by a straight electroconductive spring **31A** which is similar in construction to the spring **31**. The springs **31** and **31A** may be insulated from each other in any suitable way as by constructing the bolt **33** of insulating material or by employing insulating spacers between the bolt **33** and the springs. Under such circumstances, the insertion of the plug **8** in the receptacle **35** establishes a connection between springs **31** and **31A**. In some cases, it may be desirable to connect the springs **31** and **31A** of Fig. 3 to each other as by employing an electroconductive bolt **33** which conductively engages both of the springs.

To facilitate alignment of each of the receptacles when it is mounted on the panel **P**, a small

positioning pin **37** may be formed on each of the insulating bodies for reception in a positioning recess provided in the panel **P**.

In order to illustrate more fully the flexibility of the connection device herein described, reference is made to Fig. 4. Figure 4 shows a portion of the panel **P** which includes not only the receptacles **1**, **3**, **5** and **7**, but in addition thereto, similar receptacles **39**, **40**, **43**, **45**, **47**, **49**, **51** and **53**. It will be understood that the receptacles **39** to **45** and the receptacles **47** to **53**, respectively, are constructed in the manner described for the receptacles **1** to **7**.

Fig. 4 shows not only the flexible conductor **C** but additional conductors including the conductors **C1**, **C3**, **C5** and **C7**. All of these conductors are of similar construction. Each of the conductors has a plug **8** secured to one end thereof. In addition, the flexible conductors may be connected to desired circuit components. For example, the flexible conductors **C** and **C5** are connected respectively to the terminals of a capacitor **55**. As a further example, the conductors **C1** and **C7** are connected respectively to the terminals of a resistor **57**.

Inasmuch as the conductors **C** and **C1** have plugs inserted in the receptacles **1** and **3**, it is clear that these conductors are electrically connected through the U-shaped spring **25** (Fig. 1), which extends between the receptacles **1** and **3**. For this reason, the resistor **57** has one terminal connected to a terminal of the capacitor **55**.

The conductor **C1** has a plug **8** inserted in the receptacle **3**, and the conductor **C5** has a plug **8** inserted in the receptacle **7**. Since the latter receptacle is spaced from the receptacle **3** by an intervening receptacle which does not have a plug inserted therein, it is clear that the conductor **C1** is not connected to the conductor **C5**.

In Fig. 4, the conductor **31b** is shown connected to ground. Consequently, any of the conductors which is electrically connected to the receptacle **1** is also connected to ground.

It is believed that the flexibility and compactness of a connection device involving the invention will be clear from the foregoing description. In some apparatus such as alternating current network calculators, several hundred receptacles and a large number of plug assemblies may be employed in a single cabinet. The invention results in exceptionally compact and neat assemblies of this type and insures low resistance connections between the desired circuit components.

In a modified form of the invention the contact members **25d**, **27c**, etc. of Fig. 1 are made long enough for pairs entering each receptacle body to engage each other if no plug is present. This modification is illustrated in Fig. 5. In Fig. 5 a panel **PA** is provided with a number of receptacles, two of which **3A** and **5A** are shown. Each of these receptacles has an insulating body which may be similar in construction to the body **3a** of Fig. 1.

U-shaped electroconductive springs **25A**, **27A** and **29A** are associated with the receptacles of Fig. 5 in the same manner by which the springs **25**, **27** and **29** are associated with the receptacles of Fig. 1. However each end of the springs of Fig. 5 carries a contact member which is longer than the corresponding contact member of Fig. 1. Thus one end of the spring **27A** and one end of the spring **29A**, respectively, have contact members **27D** and **29C** which are in engagement with each other when no plug is inserted in the receptacle **5A**. If a plug having a pin

similar in shape to the pin 8a (Fig. 1) but constructed of insulating material is inserted into the receptacle 5A, the contact members 27D and 29C are separated. Such separation may be employed to interrupt a circuit which was previously completed by these springs.

The plug may be designed to connect two of the U-shaped springs independently to external circuits. In Fig. 5 such a plug 80 comprises two contact blades 80a and 80b which are insulated from each other by a strip 80c of insulation. The blades 80a and 80b are secured to the strip 80c in any suitable manner as by adhesive or by molding the blades directly into plastic insulation.

To facilitate proper orientation, the plug 80 may have a rectangular cross-section for sliding insertion in an opening 15A of rectangular cross-section provided in the receptacle 5A. The opening 15A of Fig. 5 corresponds to the opening 15 of Fig. 1.

The blades 80a and 80b may be connected to two flexible conductors 81 and 82. The connection is protected by an insulating sleeve 80d. The conductors 81 and 82 may be connected to circuit components as desired. In the specific embodiment of Fig. 5, the conductors 81 and 82 are connected to the terminals of an ammeter AM for the purpose of measuring the current flowing between the springs 27A and 29A.

Although the invention has been described with reference to certain specific embodiments thereof, numerous modifications are possible within the spirit and scope of the invention.

I claim as my invention:

1. In a connection device, a U-shaped electroconductive spring, a structure having a pair of spaced openings each defined in part by a wall portion, each of said wall portions being positioned adjacent a separate end of the spring, and each of the wall portions having a passage extending therethrough adjacent the associated spring end, said wall portions being insulated from each other, a separate contact element secured to each of said spring ends, each of said contact elements extending through the adjacent passage and projecting into the associated opening, whereby a conductor element may be moved into each of the openings to engage the associated contact element, said U-shaped electroconductive spring being proportioned to maintain the contact elements in their associated passages, whereby the contact elements serve to maintain the spring in operative position.

2. In a connection device for receiving electrical plugs, first and second spaced insulating receptacles each having an opening for reception of an electrical plug, a supporting structure for supporting the receptacles, with the openings substantially parallel, a first U-shaped electroconductive spring extending between said receptacles and having a separate leg adjacent each of the receptacles, each of said receptacles having an aperture extending from the associated opening to a position adjacent the associated leg of the spring, each of said legs having a contact end projecting therefrom through the adjacent one of said apertures and projecting into the adjacent one of the openings, said spring biasing said contact ends into said openings.

3. In a connection device for receiving electrical plugs, first and second spaced insulating receptacles each having an opening for reception of an electrical plug, a supporting structure for supporting the receptacles, with the openings

substantially parallel, a first U-shaped electroconductive spring extending between said receptacles and having a separate leg adjacent each of the receptacles, each of said receptacles having an aperture extending from the associated opening to a position adjacent the associated leg of the spring, each of said legs having a contact end projecting therefrom through the adjacent one of said apertures and projecting into the adjacent one of the openings, said spring biasing said contact ends into said openings, the spacing of said legs being sufficient to permit withdrawal of the contact ends from the apertures against the spring bias to permit removal of the spring from the receptacles.

4. In a connection device for receiving electrical plugs, first and second spaced insulating receptacles each having an opening for reception of an electrical plug, a supporting structure for supporting the receptacles, with the openings substantially parallel, a first U-shaped electroconductive spring extending between said receptacles and having a separate leg adjacent each of the receptacles, each of said receptacles having an aperture extending from the associated opening to a position adjacent the associated leg of the spring, each of said legs having a contact end projecting therefrom through the adjacent one of said apertures and projecting into the adjacent one of the openings, said spring biasing said contact ends into said openings, each of said receptacles having a channel for reception of the adjacent leg of the spring.

5. In a connection device for receiving electrical plugs, first and second spaced insulating receptacles each having an opening for reception of an electrical plug, a supporting structure for supporting the receptacles, with the openings substantially parallel, a first U-shaped electroconductive spring extending between said receptacles and having a separate leg adjacent each of the receptacles, each of said receptacles having an aperture extending from the associated opening to a position adjacent the associated leg of the spring, each of said legs having a contact end projecting therefrom through the adjacent one of said apertures and projecting into the adjacent one of the openings, said spring biasing said contact ends into said openings, in combination with a third receptacle similar in construction to said first and second receptacles and supported in spaced relationship relative to the first and second receptacles by the supporting structure, and a second U-shaped spring having contact ends similar to the first U-shaped spring and contact ends, said second U-shaped spring being associated with the second and third receptacles in the same manner by which the first U-shaped spring is associated with the first and second receptacles.

RATHBUN B. SQUIRES.
